Primary Examiner — Mark Goodwin(74) *Attorney, Agent, or Firm* — Marshall, Gerstein & Borun LLP(57) **CLAIM**

The ornamental design for a grill for a backhoe loader, as shown and described.

DESCRIPTION

FIG. 1 is a front, left-side, and top view of a grill for a backhoe loader showing one embodiment of the new design. FIG. 2 is a front, right-side, and top view of the grill for a backhoe loader.

FIG. 3 is a front, left-side, and top view showing the placement of the grill on the hood of a backhoe loader.

FIG. 4 is a front elevation view showing the placement of the grill on the hood of a backhoe loader.

FIG. 5 is a right-side elevation view showing the placement of the grill on the hood of a backhoe loader.

FIG. 6 is a left-side elevation view showing the placement of the grill on the hood of a backhoe loader.

FIG. 7 is a top plan view showing the placement of the grill on the hood of a backhoe Loader; and,

FIG. 8 is a front, right-side, and top view showing the placement of the grill on the hood.

The broken lines show environmental structure and form no part of the claimed design.

Any elements that are not clearly disclosed are not part of the claimed design.
